BENDING MACHINE

Arthur J. Mason, West Hartford, and William L. Tancred, Hartford, Conn., assignors to The Bush Manufacturing Company, Hartford, Conn., a corporation of Connecticut

Application December 6, 1932; Serial No. 645,921

8 Claims. (Cl. 153—46).

This invention relates to machines for bending tubes, and more especially to machines for bending tubes that are supplied with plates or fins for radiation purposes, and an object of the 5 invention, among others, is the provision of a machine that is simple in construction, efficient in operation and one in the use of which bends of various sorts may be formed in tubes operated upon by the machine.

10 One form of a machine embodying this invention and in the construction and use of which the objects herein set out, as well as others, may be attained is illustrated in the accompanying drawings, in which—

15 Figure 1 is a top view of a tube bending machine embodying the invention, with the upper part of the clamping shaft cut in cross section and the clamping wheel removed.

Figure 2 is a side view of the machine.

20 Figure 3 is an isometric view of the supporting disk and the bending mechanism mounted thereon in its normal position and with the retaining plate removed but placed in a nearby position.

Figure 4 is a view similar to Fig. 3, one edge 25 of the table being broken off, the retaining plate being omitted, and one former being removed but placed in a nearby position and the supporting mechanism being omitted.

Figure 5 is a top view of the supporting plate 30 with the bending and supporting mechanism in readiness for the commencement of a bending operation.

Figure 6 is a similar view showing the position 35 of the parts after the first step in the bending operation.

Figure 7 is a view similar to Fig. 6 but showing the parts set for a second step in the bending operation.

Figure 8 is a view similar to Fig. 7 but showing 40 the position of the parts after the second step in the bending operation. The retaining and spacing plate is removed in Figs. 5 to 8.

This machine is especially adapted for use in bending tubes into U-shape, and particularly in 45 forming a long bend or straight portion between the branches of the bent tube, such machine comprising a pedestal 9 supported by a base 10 and having a table 11 at its upper end on which a supporting disk 12 is secured. A bending plate 50 13 is pivotally attached at one end to the supporting disk 12, said bending plate projecting beyond the periphery of the supporting disk 12 and having a bending handle 14 secured to and projecting from its outer end.

55 A guide 15 is rigidly secured to the upper sur-

face of the plate 13 and has an undercut groove 16 which receives a movable former base 17 supporting a removable former 18 which is attached to the base as by means of pins projecting from said former into holes in the base, and as shown in Fig. 4 of the drawings. The guide 15 has secured at its end a stationary former 19. The base 17 has a notch 20 to receive a former mandrel 21 secured at the end of a rod 22, the opposite end of said rod being secured in any desirable 5 manner to retain the tip or mandrel 21 in place in the notch 20 during bending operations.

A retaining and spacing plate 23 is provided with means for holding the movable and stationary formers in different relative positions in 15 which they may be placed for bending operations, as herein shown said plate having a series of holes 24 to receive positioning pins 25 projecting from said formers, and as shown in Fig. 3 of the drawings.

20 A supporting mechanism includes a base plate 26 secured to the upper surface of the supporting disk 12, the top of said base plate being formed as a guide for a positioning plate 27 having a dove-tailed shaped rib on its under surface fitting a dove-tailed shaped groove in the upper surface of the plate 26; and as shown in Fig. 2 of the drawings. A positioning handle 28 having a positioning cam 29 is pivotally attached to the base plate 26, said cam contacting with a wear 30 plate 30 in the edge of the positioning plate 27, and as shown in Fig. 3 of the drawings.

25 A backing block 31 projects from the upper surface of the plate 27, said block having a guide groove to receive a guide rib 32 extending lengthwise along one side of a tube and fin rest 33 and by means of which said tube and fin rest are 35 adjustably secured to the block 31. This rest has a lengthwise extending groove to receive a tube to be bent, and said rest is cut away to form a 40 shoulder 34 against which the fins 35 secured to a tube 36 rest, and as shown in Fig. 5 of the drawings.

An arm 37 is secured to and rises from a supporting plate 40, said arm overarching the bending and supporting mechanism hereinbefore described and having a screw threaded hole to receive a clamp screw 38 having a hand wheel 39 as a means for operating said screw. The plate 40 is in the form of a segment and it is secured 50 to the under surface of the disk 12 with its inner end abutting the edge of the table 11 and its outer end projecting beyond the periphery of said disk 12.

55 A step 41 is attached as by swiveling to the 55

lower end of the screw 38 to make contact with the plate 23 in a manner to permit turning movement of the bending devices independently of said screw, any suitable means for supporting the screw being employed.

5 An extension table 42 rests at its inner end upon a block 43 upon the plate 40 the outer end of said table being upheld as by a leg or other suitable means, (not shown herein), a tube and the fins thereon resting upon said table during bending operations.

10 In the operation of the device a tube with fins thereon is placed in the position as shown in Fig. 5, the bend in the tube to be located in a space 15 44 between two sets of fins. The retaining plate 23 being in position with the formers 18 and 19 in contact, as shown in Fig. 5, said plate being held by the screw 38, the handle 14 is operated to turn the parts into the position shown in Fig. 20 6, thereby creating a bend of ninety degrees in the tube, and as shown in Fig. 6. In this operation, as the tube is bent around the formers, it is moved lengthwise, and this lengthwise movement is permitted by the tube and fin rest 33 25 which slides on the backing block 31 by reason of the fact that the fins 35 are in contact with the shoulder 34. This movement of the rest 33 tensions a spring 46 attached to said rest and to the table 42, said spring returning said rest to its normal position when the bending operation 30 has ceased and the tube with the fins thereon is removed from the machine.

35 The plate 23 now being removed, and the clamp screw being operated to release the parts, the formers 18 and 19 are placed in the separated position shown in Fig. 7, and the plate 23 being placed in position to retain the formers and being held by the clamp screw the handle 14 is operated to turn the parts to the position shown in Fig. 8, in which it will be noted that a straight portion 45 is formed in the bend in the tube.

40 It will be readily seen that the U-bend may be formed without displacing the formers from the positions shown in Figs. 5 and 6 in which case the bend will be circular throughout, or the formers may be placed farther apart than is shown in the drawings and held by the plate 23 in which case the straight portion 45 may be of any length desired.

45 We claim:

1. A bending machine including a support for the bending mechanism, said bending mechanism including a movably mounted bending member, a plurality of formers mounted on said bending member and separable one from another thereon, means for retaining said formers in different relative positions during bending operations on said bending member, and means for engaging articles to be bent with said formers.
2. A bending machine including a support for the bending mechanism, said bending mechanism including a rotatably mounted bending member, a plurality of formers mounted on said bending member and separable one from another thereon, a retainer engageable with said formers to retain them in different relative bending positions during bending operations to vary the sizes of bends on said bending member, and means for engaging articles to be bent with said formers.

3. A bending machine including a support for bending mechanism, said bending mechanism including a bending member, formers mounted on and carried by said bending member, one of said formers comprising a portion of a hub around which the article is bent and another former comprising two members together forming a portion of said hub and having means to receive the article to be bent, means for retaining said formers in different relative bending positions, and means for engaging articles to be bent with said formers.

4. A bending machine including a support for the bending mechanism, said bending mechanism including a rotatably mounted bending member, a guide secured to and carried by said bending member, a former rigidly attached to said guide, a former movably mounted on said guide, a retainer engageable with said formers to retain them in different relative bending positions during bending operations to vary the sizes of bends, and means for engaging articles to be bent with said formers.

5. A bending machine including a support for the bending mechanism, said bending mechanism including a rotatably mounted bending member, a guide rigidly secured to said bending member, a one-piece former rigidly secured to said guide, a two-piece former movably mounted on said guide, a retainer engageable with said formers to retain them in different relative bending positions during bending operations to vary the sizes of bends, and means for engaging articles to be bent with said formers.

6. A bending machine including a support for the bending mechanism, said bending mechanism including a bending member, formers mounted on said bending member and separable one from another, a retaining plate, engageable pins and holes on said formers and bending plate to hold the formers in different relative bending positions, and means for engaging articles to be bent with said formers.

7. A bending machine including a support for the bending mechanism, said bending mechanism including a bending member, formers mounted on said bending member to form a bend in an article, one of said formers being movable with respect to the other, means for retaining said formers in different relative bending positions, article supporting mechanism positioned adjacent to said formers, and means for positioning said supporting mechanism to accord with different positions of said movable former member.

8. A bending machine including a support for the bending mechanism, said bending mechanism including a bending member, formers mounted on said bending member to form a bend in an article, one of said formers being movable with respect to another, means for retaining said formers in different relative bending positions, article supporting mechanism positioned adjacent to said formers, means for positioning said supporting mechanism to accord with different positions of said movable former member, and a rest for the article to be bent, said rest being movable toward and away from said formers.

ARTHUR J. MASON.
WILLIAM L. TANCRED.
